United States Patent Office.

ANSON MERRIMAN, OF NEW YORK, N. Y.

Design No. 3,955, dated April 5, 1870.

DESIGN FOR BRAKE-WHEELS.

The Schedule referred to in these Letters Patent and making part of the same.

I, ANSON MERRIMAN, of the city, county, and State of New York, have invented and produced a new and original Design for Brake-Wheels, of which the following is a specification.

The nature of my design is fully represented in the accompanying photographic illustration, to which reference is made.

I claim as my invention—
The design for a brake-wheel, as shown.
ANSON MERRIMAN.
